his Attorney's

UNITED STATES PATENT OFFICE.

BENJAMIN A. CHEW, OF AUGUSTA, GEORGIA.

COTTON-PICKER.

No. 843,968.

Specification of Letters Patent.

Patented April 2, 1907.

Application filed November 5, 1906. Serial No. 342,856.

To all whom it may concern:

Be it known that I, BENJAMIN A. CHEW, a citizen of the United States, residing at Augusta, in the county of Richmond and 5 State of Georgia, have invented certain new and useful Improvements in Cotton-Pickers; and I do hereby declare the following to be a full, clear, and exact description of the same, reference being had to the accompanying 10 drawings, forming a part of this specification, and to the figures and letters of reference marked thereon.

This invention relates to cotton-pickers of that type wherein the cotton is detached 15 from the bolls by mechanical means directed by the hand of an attendant and when detached is conveyed to a suitable receptacle, the conveying means usually and preferably employed consisting of a flexible conduit 20 through which the cotton is drawn by air-suction.

The object of the invention of this application is to improve the picker or nozzle portion of the picker described in my contemporaneous application, Serial No. 318,341, 25 filed May 23, 1906, and hence the drawings illustrate simply the said portion of the apparatus.

In the drawings, Figure 1 is a side elevation 30 of a picker-nozzle embodying the present improvements. Fig. 2 is a bottom plan view, Fig. 3 is a section longitudinally of the nozzle.

Similar letters of reference in the several 35 figures indicate like parts.

The flexible pipe or conveyer-duct is indicated by the letter A and its nozzle end by the letter B. The nozzle end is provided with two openings, one in line with the conduit for the admission of air alone and the size of which may be regulated by a disk or other suitable valve C, adapted to be controlled by the attendant through a handle or finger-piece C'. The other or cotton- 40 admission opening in the nozzle is a transverse opening through which the cotton is pushed by the mechanically-operated portions of the picker, so as to force the same into the air-current by which it is carried 45 into the common receptacle.

The cotton-admission opening is surrounded by a bell-mouth frame D, which for the sake of lightness may be an aluminium casting. The bell-mouth frame is provided 50 with projections D', in which are the bearings for saw or picker shafts E, arranged in a

quadrangle and connected in series by bevel-gears E'. Each shaft carries a saw or picker F, which on one side projects into the bell-mouth, the diameter of the saws and 55 the location of the shafts being such that the edges of the saws or pickers project into the pipe or conduit itself and pass out through narrow slits, whereby the air-current will effectually clear or clean the saws, and no 60 other clearing means is usually found necessary or desirable.

Portions D² of the bell-mouth frame preferably extend around the saws to protect the same; but the saws are exposed at points 65 in proximity to the bell-mouth to facilitate the entanglement of the cotton. The edge of the bell-mouth preferably terminates within the peripheries of the saws or pickers. In other words, the peripheries of the saws 70 or pickers project beyond the edge of the bell-mouth to entangle the cotton; but by reason of the fact that these portions of all the pickers move toward a common center the cotton is carried to the center of the bell-mouth and enters the same before the air-suction materially affects the same. As a result the liability of picking up leaves, 75 trash, and dirt, which will entangle with the saws, is very much reduced. The saws, 80 it will be noted, are preferably set with the teeth reversely inclined to their direction of rotation, and this is preferably the case regardless of whether the teeth are solid or pivoted, as has heretofore been proposed. 85 With the teeth so set they will successfully entangle the cotton, but operate to repel all matter not of a fibrous nature.

In the present arrangement one of the shafts E is in line with the power-shaft H and 90 may be directly connected thereto, thus requiring but three sets of bevel-gears to drive all the shafts. The power-shaft usually extends parallel with the pipe or conduit to a suitable source of power, and bearings, as at 95 K, may be provided for maintaining the proper relation of the pipe and shaft.

For handling the nozzle end it may be provided with a handle L of any suitable construction.

To assist in clearing the saws of adherent fiber as well as to insure the surrounding of the lint with an envelop of moving air, air-openings H' are formed around the inner part of the bell-mouth in position to direct the incoming air against the lint in a direction tending to release the same from the saws.

Springs I, secured to the inside of the bell-mouth on each side of the saws, may also be used to assist in removing the lint from or clearing the saws.

5. Having thus described my invention, what I claim as new, and desire to secure by Letters Patent, is—

1. In a pneumatic cotton-picker the combination with the nozzle having a substantially straight passage therethrough and a bell-mouth cotton-entrance at one side of and opening transversely into said substantially straight passage, of toothed rotary pickers journaled at an angle to each other around the bell-mouth and having their peripheries projecting into both the bell-mouth and the substantially straight passage through the nozzle for mechanically carrying the cotton entirely through the bell-mouth and delivering the same into the passage.

2. In a pneumatic cotton-picker the combination with the nozzle having an air-passage therethrough and a bell-mouth cotton-entrance at one side of and opening transversely into said air-passage, of toothed rotary pickers journaled at an angle to each other around the bell-mouth, said pickers being of greater diameter than the length of the bell-mouth, and having their peripheries projecting into the bell-mouth and beyond each end of the same, whereby the cotton will be engaged before it enters the bell-mouth and will be carried by the pickers entirely through the bell-mouth and into the air-passage.

3. In a cotton-picker, the combination with the nozzle end of the duct having a valved air-inlet and a transverse cotton-inlet, of a bell-mouth frame secured to one side of the nozzle around the cotton-inlet and having shaft-bearing projections on four sides thereof, picker-shafts and pickers journaled in said bearings and connected by gearing for simultaneous rotation and a power-shaft mounted in alignment with one of said picker-shafts.

4. In a cotton-picker, the combination with the nozzle end of the duct having an air-inlet in the end and a transverse cotton-inlet, and a bell-mouth frame secured around the cotton-inlet and having shaft-bearing projections, of picker-shafts arranged in a quadrangle in said frame and connected by gearing, a drive-shaft in line with and connected to one of said picker-shafts.

5. In a cotton-picker, the combination with the nozzle end of the duct having an end air-opening a lateral cotton-inlet opening and a bell-mouth frame surrounding the cotton-inlet opening, there being radial-picker-saw slits extending longitudinally through the frame and through the wall of the nozzle, of radial picker-saws journaled in the frame and having their peripheries projecting into the nozzle and bell-mouth and beyond the outer edge of the bell-mouth; substantially as described.

6. In a pneumatic cotton-picker, the combination with the nozzle end of a suction conveyer, of a bell-mouth forming a cotton-entrance opening, picker-saws projecting into said opening and yielding clearers between which the picker-saws pass to free the cotton therefrom.

7. In a cotton-picker, the combination with the nozzle end of a suction conveyer-duct, of a bell-mouth forming the cotton-entrance opening, mechanically-operated picker-saws projecting into said bell-mouth and backwardly-inclined yielding clearers between which the picker-saws pass after entering the bell-mouth; substantially as described.

8. In a cotton-picker, the combination with the nozzle end of the suction duct having the bell-mouth cotton-entrance opening and an air-port in proximity to the inner end of said bell-mouth, of the toothed rotary picker having its periphery projecting into the bell-mouth and extending inwardly past the air-port whereby air entering through said port will assist in clearing the cotton from the picker.

9. In a cotton-picker, the combination with the nozzle end of the suction duct having the bell-mouth cotton-entrance opening and a plurality of air-ports around the base of the bell-mouth, of a plurality of rotary toothed pickers journaled in angular relation around the bell-mouth and having their peripheries projecting into said bell-mouth and extending inwardly past the air-ports, whereby air entering said ports will clear cotton from the pickers.
